Inventor:

Robert P. Lamont

By Paul Symes

Atty.

UNITED STATES PATENT OFFICE.

ROBERT P. LAMONT, OF CHICAGO, ILLINOIS, ASSIGNOR TO SIMPLEX RAILWAY APPLIANCE COMPANY, OF CHICAGO, ILLINOIS, A CORPORATION OF ILLINOIS.

FULCRUM-BLOCK FOR BRAKE-BEAMS.

SPECIFICATION forming part of Letters Patent No. 782,970, dated February 21, 1905.

Application filed July 25, 1903. Serial No. 166,933.

To all whom it may concern:

Be it known that I, ROBERT P. LAMONT, a citizen of the United States, residing at Chicago, in the State of Illinois, have invented a 5 certain new and useful Fulcrum-Block for Brake-Beams, of which the following is a specification.

My invention relates to railway brake gear, and particularly to the means for attaching 10 the brake beam at its fulcrum point to the pull rods or levers, and consists primarily in the construction of the fulcrum block. The objects of the invention are, to provide a rigid and strong fulcrum block made in one piece; 15 to provide a forged integral fulcrum block which may be readily secured to and firmly fixed on the brake beam; to provide such a fulcrum block of a form to be snugly secured to an I-beam and not relying upon rivets to take 20 up the shear, and to reduce the cost and generally improve the construction of fulcrum blocks.

The above objects, together with other advantages which will hereinafter appear, I attain in the structure illustrated in preferred 25 form in the accompanying drawings, wherein—

Figure 1 is a side elevation of the fulcrum block, shown partly in section, and mounted 30 upon the I-beam;

Figures 2 and 3 are respectively an under and a top plan view of the block;

Figures 4 and 5 are respectively a plan and 35 an edge view of the blank from which the block is made.

I prefer to make the fulcrum block of wrought iron or soft steel. The blank may be cut from sheet metal in the form shown in Figures 4 and 5, and preferably the arms 7 and 40 10 are of about the same width, as shown. The arms 7 are bent perpendicularly to their length so as to conform to the flange of the I-beam 5, and the arms 10 and 11 are given a sharp bend at the edge of a base portion 9 and 45 brought up parallel with each other as shown in Figure 1 and given a twist of about 40 degrees as shown in Figure 2.

It will be observed that the arms 10 and 11

are laterally displaced from position opposite to each other about half of their width. They 50 may be trimmed round if desired, and preferably the rivet holes 12, and the holes for the attaching rivet 8 are punched in both their respective pairs of arms at once.

It will be observed that this construction is 55 extremely simple and the article may be sheared and forged conveniently from the ordinary rolled plates found in the market and when completed is extremely rigid and strong. The arms 7 having been put upon the I-beam 60 it will be noticed that the shoulders take the pulling strain against the flange, so that the rivet 8 is required only to hold them from spreading and from lateral displacement on the beam. The many advantages of this construction will readily occur to those familiar 65 with the use of such devices.

Having thus described my invention and its use, what I claim, and desire to secure by Letters Patent, is the following:

1. A single piece fulcrum block formed of plate metal and forged with two pairs of arms oppositely bent respectively to embrace the beam and to form the fulcrum jaws, said arms being of the same thickness with each other 75 and with the fulcrum seat.

2. A fulcrum block formed of forged plate metal comprising two attaching arms for the beam and two separate arms for the fulcrum jaws bent oppositely, substantially as described.

3. A single piece fulcrum block comprising two arms to embrace the brake beam and two fulcrum jaws, the latter jaws being laterally offset with respect to each other at their juncture with the seat of the block, substantially as described.

4. A brake beam fulcrum block comprising a single piece of forged plate metal, having four arms, two of which are in alinement with 90 each other and the other two being laterally offset with respect to each other and the two pairs of arms being bent in opposite directions, substantially as described.

5. A brake beam fulcrum block blank, comprising two arms extended in line opposite to

each other, and two arms extending approximately at right angles to the line of the first two but laterally displaced from direct alinement to each other.

5 6. A brake fulcrum block blank comprising two oppositely extending arms in alinement, and two oppositely extending arms having their bases laterally displaced from the center of the blank and their outer ends respectively 10 opposite to each other on a line perpendicular

to the center of the blank substantially as and for the purpose described.

In testimony whereof I have hereunder signed my name in the presence of the two subscribed witnesses.

ROBERT P. LAMONT.
